UNITED STATES PATENT OFFICE

FRANCIS X. GOVERS, OF LAWRENCEVILLE, ILLINOIS, ASSIGNOR TO INDIAN REFINING COMPANY, OF LAWRENCEVILLE, ILLINOIS, A CORPORATION OF MAINE

HEAT TRANSFER TUBE

Application filed November 5, 1928. Serial No. 317,300.

This invention relates to tubes through whose walls heat is to be transferred.

It is, of course, well known to provide tubes intended for this purpose with longitudinally extending fins to afford additional surface.

My invention relates to the particular construction of such a tube whereby it is easily made, and is so constructed that its end or ends can easily be secured into a tube-sheet, as by the expansion method or by electric welding.

In the drawings:

Fig. 1 is a longitudinal section;

15 Fig. 2 is an enlarged cross-section on plane 2, 2 of Fig. 1;

Fig. 3 is a sectional detail of a portion of a tube-sheet, and

20 Fig. 4 is a longitudinal section of a modified form.

The tube is made from a length of pipe, advantageously seamless steel tubing, of a given substantially uniform outside diameter and bore. The end portions of the bore may be enlarged as by boring out to form a chamber or chambers 1, 1 large enough to afford access to the expanding tool, by which the end or ends are expanded into the grooves 2, of an opening in a tube sheet 3.

30 Ribs 4, 4 are formed on the outside of the tube by cutting away the metal of the tube, between the end portions. The overall peripheral diameter of the tube is thus unchanged, but portions of the metal have been removed from the inside at the end or ends to adequately enlarge the bore for the purpose stated, and portions of the metal have been removed from the outside to form the ribs, and thus largely increase the surface.

40 If it be preferred to electrically weld the tube into the tube-sheet, the enlargement or chamber 1 may be omitted, as shown in Fig. 4.

I claim:

45 1. A heat-transfer tube having an overall peripherally uniform diameter, a bore of circular cross-section throughout its length, and longitudinally extending exterior ribs, whose outer ends are within said periphery, said ribs being of less length than the tube.

50 2. A heat-transfer tube having an over-

all peripherally uniform diameter, a bore of circular cross-section throughout its length and enlarged at its ends, and longitudinally extending exterior ribs, whose outer ends are within said periphery.

55 3. A heat-transfer tube as claimed in claim 1, in which the ribs are formed by removing the metal of the tube between the ribs.

In testimony whereof, I affix my signature.

FRANCIS X. GOVERS.
